UNITED STATES PATENT OFFICE

141,078

DESIGN FOR A GUN

Charles S. Wheatley, Boston, Mass.

Application January 23, 1945, Serial No. 117,557

Term of patent 14 years

(Cl. D30--1)

To all whom it may concern:

Be it known that I, Charles S. Wheatley, a citizen of the United States, residing at Boston, in the county of Suffolk and State of Massachusetts, have invented a new, original, and ornamental Design for Guns, of which the following is a specification, reference being had to the accompanying drawing forming part thereof.

In the drawing:

Fig. 1 is a side elevational view of a gun showing my new design;

Fig. 2 is a top plan view;

Fig. 3 is a bottom plan view; and

Fig. 4 is an end elevational view as seen from the butt end.

The dominant features of the present design reside in the barrel and stock portions of the gun.

I claim:

The ornamental design for a gun, substantially as shown and described.

CHARLES S. WHEATLEY.
